ARVID M. ANDERSON, OF BROOKLYN, NEW YORK, ASSIGNOR TO TINSEL CORPORATION OF AMERICA, OF BROOKLYN, NEW YORK, A CORPORATION OF NEW YORK.

CHENILLE-MAKING MACHINE.

Application filed June 20, 1925. Serial No. 38,449.

This invention relates to improvements warp threads 6 are drawn in the direction in machines for making chenille generally, of the arrows to form parts of the cores of and, particularly, to machines for making chenille for various purposes of ornamentation wherein the pile thereof is formed of tinsel threads.

The object of the invention is to improve the means for carrying the pile-forming threads and delivering them to the core around which they are wound in the formation of the pile of the chenille. The invention aims to provide a machine which will produce a superior product and to eliminate the objectionable necessity of delivering two or more threads from a single spool to provide the requisite number of threads for the formation of the desired pile, and to so construct and arrange the parts for carrying the threads for forming the pile with relation to the pile forming elements of the machine that a single thread may be delivered from each of the spools supplying the pile threads for the production of chenille having the desired numerous pile threads.

With the forgoing and related objects in view, the invention resides in the novel construction, combination and arrangement of parts hereinafter described and claimed.

In the accompanying drawings, illustrating my invention.

Figure 1 is a side view of a portion of a chenille making machine embodying my invention.

Figure 2 is a horizontal section of the machine, on line 2-2 of Fig. 1.

Figure 3 is a diagrammatic view showing the arrangement of the pile thread spools and the manner in which the pile threads are delivered therefrom to the central thread guiding ring.

Figure 4 is a side view of the core plates around which the pile threads of the chenille are wrapped.

Referring to the drawings, 3 designates the frame of the machine which is provided with a fixed bearing or bracket 4.

Secured within the bearing 4 is the rearward end portion of a horizontally arranged, hollow shaft 5 through which two

Secured to the forward end portion of the hollow shaft 5 are the oppositely disposed vertical members 8 of two angle plates 9 having forwardly extending horizontal members 10 between which is secured a core plate 11 for receiving the threads for forming the pile of the chenille. The horizontal members 10 of the angle plates 9 have wing portions 12 which extend outwardly beyond the sides of the forward end of the core plate 11 and which are shaped to provide inclined sides which converge forwardly to the sides of the core plate, as shown in Fig. 2. The core plate 11 extends forwardly from the wings 12 and the warp threads 6 are guided by and between the upper and lower wings 12 along the sides of the plate 11, in close proximity thereto, to and between the sides of the plate 11 and a pair of horizontally disposed guiding wheels 13 arranged outwardly of the sides of the forward end portion of the plate 11 in spaced relation to the wing portions 12 of the angle plates 9, as clearly shown in Fig. 2.

The peripheries of the wheel 13 are circumferentially grooved to receive the warp threads and the side edge portions of the core plate 11, and also to receive two wires 14 drawn from a suitable source over a guide rod 15 to and through the grooves in the wheels 13 and around the rearward portions thereof until they meet the warp threads 6 between the plate 11 and wheels 13.

After the wires 14 meet the warp threads 6 they are drawn onwardly with them in the direction of the arrows and the wires and threads are twisted together from and beyond about the points where they meet, to form the cores of two strands of chenille, in the usual well known manner.

The wheels 13 are carried by the rearward arms 16 of two levers 17 which are fulcrumed on a vertically extending shaft 18 which is supported by the machine frame. The levers 17 cross each other and the rearward arm 19 of one of the levers 17 has a rod 20 pivotally connected thereto which ex-

tends slidably through and beyond a part of the rearward end of the arm 21 of the other lever 17. The free end of the rod 20 carries a head 22 between which and the lever arm 21 a spring 23 encircles the rod 20 and tends to move the lever arms 19 and 21 toward each other, thereby tending to move the lever arms 16 and the wheels 13 carried thereby toward each other. Thus the spring 23 holds the wheels 13 yieldingly in contact with the sides of the core plate 11 or in contact with the wires 14 and threads 6 passing between the sides of the core plate 11 and the wheels 13.

15 Arranged within an opening in the forward end portion of the core plate 11 and between the guiding wheels 13 is a pair of co-operating cutter discs 24. The lower disc 24 is mounted to turn on an arm 25 which is fixed to the vertical shaft 18, and the upper disc 24 is mounted to turn on an arm 26 which is carried by the shaft 18 and adapted to turn on the axis thereof, so that the upper disc 24 may be pressed yieldingly against the lower disc 24 by the action of a spring 27 which encircles the shaft 18 and which has its lower end engaged with the arm 26 and its upper end engaged with a collar 28 fixed on the shaft 18.

20 The threads which are to form the pile of the chenille are wrapped around the core plate 11 and the warp threads 6 passing along the sides thereof, and they are carried by the threads 6 into the bite of the cutter discs 24 which are located slightly in advance of a line drawn between the centers of the wheels 13 to cut or sever the pile threads at the proper place with relation to the passage of the pile threads between the core threads 6 and core wires 14, and the twisting of the threads 6 and wires 14 for the proper formation of the chenille. The cutter discs 24 are adapted to be driven in the usual manner during the operation of the machine to effect the cutting operation.

25 The construction and operation of the parts thus far described are well known to persons skilled in this art, and, therefore, no detailed description thereof is deemed necessary herein.

30 I shall now describe the means forming the subject of my invention for carrying the pile forming threads and delivering them to and wrapping them around the core plate 11 and the forwardly moving warp threads 6.

35 Rotatably mounted on the hollow shaft 5 between the bearing 4 and a flange or collar 7 on the forward end of the shaft 5 is a sleeve 30 which carries a member 31 comprising a disk-like body 32 and a central sleeve or hub 33 which is secured to the sleeve 30 by means of a set screw 34, whereby, when the sleeve 30 is rotated, the

member 31 will be rotated. The sleeve 30 has a gear wheel 35 formed thereon by means of which it may be rotated by the driving mechanism of the machine.

40 The rotatable member 31 carries an inner, annular series of thread supplying spools 36 and an outer, annular series of thread supplying spools 37 which surrounds the inner series.

45 The spools 36 and 37 of the inner and outer series are mounted to turn on spindles 38 and 39, respectively, which project fixedly from the member 31; and the free end portions of the spindles 38 and 39 are provided with pins 40 which extend transversely through openings therein and which retain the spools upon the spindles. Washers 41 are interposed between the pins 40 and the spools and the pins 40 and washers 41 are removable from the spindles to permit filled spools to be placed thereon and empty spools to be removed therefrom.

50 Projecting forwardly from the forward end of the sleeve or hub 33 of the rotatable member 31 is a pair of arms 42 carrying a ring 43 arranged concentric with the axis of rotation of the member 31 to guide or guard pile-forming threads delivered from the spools 36 and 37, as will be presently described.

55 The axes of the spindles 38 and 39 and the spools 36 and 37 carried thereby are inclined with respect to the axis of rotation of the member 31 and they diverge from the forward face of the body 32 of the member 31 and from the axis of rotation of the member, as clearly shown in the drawings, and the axes of the outer spindles 39 and spools 37 are more nearly parallel to the axis of rotation of the member 31 than the axes of the inner spindles 38 and spools 36, as illustrated.

60 The spools 37 of the outer series thereof are more numerous than the spools 36 of the inner series, and the axes of pairs of next adjacent spools 39 of the outer series intersect separated lines which radiate from the center of the member 31 and pass between the axes of pairs of next adjacent spools 36 of the inner series, so that threads 45 drawn from two next adjacent spools 39 of the outer series may pass between two next adjacent spools 36 of the inner series to the ring 43 without contacting with the spools 36 or the threads carried thereby, and so that threads 46 drawn from the inner spools 36 may pass to the ring 43 without contacting with the threads drawn from the outer spools 39, as shown in Fig. 3.

65 During the rotation of the member 31 the pile-forming threads 45 and 46 are drawn from the spools 39 and 36 and wrapped around the core plate 11 and the warp threads 6 moving forwardly along the sides thereof, and the pile threads 45 and 46 are

carried forwardly by the threads 6 as rapidly as the convolutions of the pile threads are formed around the core plate 11 and threads 6. The relation of the axes of the spindles 5 38 and 39 to the axis of rotation of the member 31 is such that the spools 36 and 37 and washers 41 are pressed against the pins 40 by centrifugal action with sufficient force to create enough friction between the 10 parts to retard the turning movements of the spools 36 and 37 sufficiently to cause the threads 45 and 46 to be drawn from the spools under the desired degree of tension.

The axes of the inner and outer spools 36 15 and 37 are so disposed with respect to the ring 43 that, as the threads 45 and 46 are drawn from the spools to the core plate 11, each thread 45 and 46 will maintain substantially a constant angle with respect to 20 the axis of rotation of the member 31, and each thread 45 and 46 will be permitted to be delivered from all parts of its spool between the ends thereof without substantially 25 varying the length of that portion of each thread which extends between its spool and the guiding ring 43, thereby preserving substantially a constant tension on all threads 45 and 46.

The member 31 is adapted to be rotated 30 by the usual mechanism of the machine geared to the wheel 35, and, during its rotation, the pile forming threads 45 and 46 are drawn from the spools 37 and 36, formed into convolutions around the core plate 11 and warp threads 6, the convolutions are carried forwardly by the warp threads 6 to the wires 14 and cutter discs 24, the convolutions are centrally cut by the discs 24 and the cut convolutions are bound between 40 the twisted threads 6 and wires 14 to form two strips of chenille.

I claim as my invention:—

1. In a chenille making machine the combination of a supporting frame, a core for receiving pile-forming threads, a rotatable member, an annular series of spools carried by the member for delivering threads to the core, and a second annular series of thread supplying spools carried by the member, and surrounding the first named series, for delivering threads to the core, the axes of the spools of each series being inclined with respect to the axis of rotation of the member, and the inclinations of the axes of the spools of the outer series being more nearly parallel to the axis of rotation of the member than the inclinations of the axes of the spools of the inner series.

2. In a chenille making machine the combination of a supporting frame, a core for receiving pile-forming threads, a rotatable member, an annular series of spools carried by the member for delivering threads to the core, and a second annular series of thread supplying spools carried by the member, and

surrounding the first named series, for delivering threads to the core, the spools of the outer series being more numerous than the spools of the inner series, and the axes of pairs of next adjacent spools of the outer series intersecting separate lines which radiate from the center of said member and pass between the axes of pairs of next adjacent spools of the inner series, whereby threads delivered from a pair of spools of the outer series may pass between a pair of spools of the inner series without making contact therewith.

3. In a chenille making machine the combination of a supporting frame, a core for receiving pile-forming threads, a rotatable member, an annular series of spools carried by the member for delivering threads to the core, and a second annular series of thread supplying spools carried by the member, and surrounding the first named series, for delivering threads to the core, the spools of the outer series being more numerous than the spools of the inner series, the axes of the spools of each series being inclined with respect to the axis of rotation of the member, and the axes of pairs of next adjacent spools of the outer series intersecting separate lines which radiate from the center of said member and pass between the axes of pairs of next adjacent spools of the inner series, whereby threads delivered from a pair of spools of the outer series may pass between a pair of spools of the inner series without making contact therewith.

4. In a chenille making machine the combination of a supporting frame, a core for receiving pile-forming threads, a rotatable member, an annular series of spools carried by the member for delivering threads to the core, and a second annular series of thread supplying spools carried by the member, and surrounding the first named series, for delivering threads to the core, the spools of the outer series being more numerous than the spools of the inner series, the axes of the spools of each series being inclined with respect to the axis of rotation of the member, the inclinations of the axes of the spools of the outer series being more nearly parallel to the axis of rotation of the member than the inclinations of the axes of the spools of the inner series, and the axes of pairs of next adjacent spools of the outer series intersecting separate lines which radiate from the center of said member and pass between the axes of pairs of next adjacent spools of the inner series, whereby threads delivered from a pair of spools of the outer series may pass between a pair of spools of the inner series without making contact therewith.

5. In a chenille making machine the combination of a supporting frame, a core for receiving pile-forming threads, a rotatable

member, rearwardly of the core, two sets of spools carried by the member for delivering threads to the core, each set being arranged in an annular series separated from the other 5 and the axes of the spools of each series being inclined with respect to the axis of rotation of the member, and a thread guiding ring carried by the member concentric with the axis of rotation thereof and positioned forwardly of the said spools to receive threads directly therefrom and to deliver them to said core. In testimony whereof I affix my signature hereto.

ARVID M. ANDERSON.
